UNITED STATES PATENT OFFICE.

ELMER L. SMITH, OF SPRINGFIELD, MASSACHUSETTS, ASSIGNEE TO PACKAGE MACHINERY COMPANY, OF SPRINGFIELD, MASSACHUSETTS, A CORPORATION OF MASSACHUSETTS.

WRAPPING-MACHINE.

1,306,358.

Specification of Letters Patent. Patented June 10, 1919.

Application filed March 2, 1918. Serial No. 219,985.

To all whom it may concern:

Be it known that I, ELMER L. SMITH, a citizen of the United States, and a resident of Springfield, in the county of Hampden and State of Massachusetts, have invented 5 certain new and useful Improvements in Wrapping-Machines, of which the following is a specification.

This invention relates to wrapping machines, and more particularly to such machines wherein articles, as well as additional material, such as advertising circulars, pamphlets, cards and the like, may be inclosed within the wrapper. The invention 10 also relates to machines for wrapping articles having a more or less oval shape or such articles which, due to the lack of square end faces, are not readily wrapped by ordinary means.

20 One object of the invention is to provide a machine which will automatically supply to and apply about the articles and within their outer wrappers, any desired number of inclosures such as descriptive circulars, 25 advertising pamphlets, cards and the like, and the machine is characterized in that the articles may be successively wrapped with a plurality of inclosures in such a manner that the overlapped seams of successive 30 wrapped inclosures lie on opposite sides of the article.

Another object of the invention is to provide a machine capable of successfully wrapping articles, the end faces of which are 35 more or less rounded, irregular, or otherwise formed, so that the end folds of the wrapper cannot be laid squarely against the ends of the articles by ordinary means. According to this feature of the invention, I 40 provide automatic means for forming a container or sleeve of relatively stiff material, such as cardboard and the like, which container is substantially co-extensive in length with the articles and "builds out" the rounded ends of the articles, so that a smooth, 45 closely wrapped package may be obtained by thereafter wrapping the container in the usual manner with overlapping end folds.

A further object of the invention is to

provide, in combination with automatic 50 means for forming a containing tube for the article by folding a strip of relatively stiff material, such as a cardboard sleeve and the like, about the article, means to apply a retaining band about the folded container 55 to hold the latter in tube-forming position independently of the outer and subsequently applied wrapping.

A further object of the invention is to provide improved means for simultaneously 60 feeding a plurality of articles step by step in spaced relation, characterized by a plurality of spaced article-engaging members movable simultaneously by a single mechanism in a closed loop path, which is intersected by the path of the articles, each member being arranged to move an article one step into a position to be engaged on a subsequent cycle of operation by the next-successive member.

70 A further object of the invention is to provide in combination with mechanism for forming gummed overlapped seams, an improved type of discharge apparatus through which the articles may be conveyed from 75 said mechanism and the overlapped seams of their wrappers firmly held until the adhesive has set.

Other objects and advantages will appear in the following description and in the illustrative embodiment of the invention in the accompanying drawings, in which—

80 Figures 1^a and 1^b are general elevational views of the left and right hand portions of the machine. These two views, shown separately on account of scale considerations, should be imagined as joined one to the other to afford a complete view of the machine. These views, in the main, show a longitudinal sectional view of the machine, 85 although certain parts are shown merely in exterior elevation, and many of less essential parts have been broken away to more clearly disclose other and more essential parts;

85 Figs. 2 to 8, inclusive, are perspective views showing the article with its wrappings as it appears in various positions during its passage through the machine;

Fig. 9 is a sectional elevational view illustrative of the mechanism for feeding the folded circulars to the articles;

Fig. 10 is a fragmentary perspective view 5 of a part of Fig. 9;

Fig. 11 is a cross-sectional view taken on the line 11—11 of Fig. 9;

Fig. 12 is a sectional elevational view of 10 the first tumble-box, and is taken on a different plane than Fig. 1 to illustrate the operating connections for the tumble-box ejector;

Fig. 13 is a fragmentary sectional plan view of Fig. 12;

Fig. 14 is a fragmentary plan view of the 15 second tumble-box;

Fig. 15 is a fragmentary plan view illustrative of the operating mechanism for affixing stamps or stickers to the overlapped ends of the retaining bands which hold the 20 previously applied wrappings to the articles;

Fig. 16 is a cross-sectional view taken on the line 16—16 of Fig. 1^a and illustrates the stamp-affixing mechanism;

Fig. 17 is a fragmentary plan view of a 25 part of Fig. 16;

Fig. 18 is a fragmentary sectional plan view of a part of Fig. 17;

Fig. 19 is a detail view of a moistener used in the stamp-affixing mechanism;

Fig. 20 is a fragmentary enlarged sectional view of a part of Fig. 16 showing a 30 different positioning of parts and illustrating the stamp-feeding mechanism;

Fig. 21 is an elevational view of the right-hand end of the structure shown in Fig. 17;

Fig. 22 is a detail view of the severing blade shown in Fig. 20;

Fig. 23 is a detail view of the yieldable 40 jaw of the stamp-gripping mechanism shown in Fig. 20;

Fig. 24 is a plan view of the continuous strip of stamps as supplied to the machine;

Fig. 25 is a fragmentary elevational view 45 of the exterior of that portion of the machine adjacent the third tumble-box and end folding mechanism;

Fig. 26 is a plan view, partly in section, of the discharge apparatus for holding the gummed overlapped end folds until the adhesive has set; and

Fig. 27 is a cross-sectional view taken on the line 27—27 of Fig. 26.

The machine, in general, comprises a series of aligned chutes or passageways through 55 which the articles to be wrapped may travel; a plurality of feeding mechanisms to supply material to be applied to the articles and position the material in the path of the articles; a series of spaced tumble-boxes to 60 transfer articles from certain chutes to others and assist in wrapping the material about the articles; sealing devices to operate on certain of the wrapped material while the articles are in the chutes; end folding

mechanism and end fold sealing devices like- 65 wise operable while the articles are confined in a chute; a chute forming discharge apparatus to hold the sealed end folds for a sufficient interval to permit the adhesive to set; and a plurality of transferring devices to 70 move the articles through the chutes and into and out of the tumble-boxes in properly timed relation.

Considering the machine somewhat more specifically in connection with the work 75 which it, in its present illustrative embodiment, is adapted to perform,—articles *a*, such as cakes of soap or the like, are passed in a straight line from one end of the machine to the other, and during their passage various material is fed and applied to the articles. First, a length of cardboard *b* and a previously-folded advertising circular *c*, each of which, as shown in Fig. 2, is substantially equal in width to the length of the 80 article, are simultaneously wrapped around the sides of the article and overlapped, forming a joint *d* (Fig. 3). The ends of articles *a*, as illustrated, are more or less rounded, and the cardboard *b* acts to build out these 85 rounded edges so that the ends of the package may be made square to permit neat and smooth end folding of an outer wrapper subsequently to be applied. After the cardboard *b* and circular *c* have been entirely 90 wrapped about article *a*, a narrow band *e* is wrapped about the circular *c*, and, as clearly indicated in Fig. 4, the ends of band *e* overlap, as at *f*, on the side opposite from joint *d*. The overlapped ends *f* are then 95 joined by the application of a stamp or 100 sticker *g* so that the band and stamp may operate to retain circular *c*, and more particularly the relatively stiff cardboard *b*, in 105 closely wrapped relation with the article *a*. The article now has been inclosed in a container or sleeve, leaving only its ends exposed, and by first building up a container out of relatively stiff material, an article 110 which by itself is not readily wrapped on account of irregularities or rounded corners, may now be smoothly wrapped in the usual manner.

The next step consists in the application 115 of an outer wrapper *h* which is first applied around the previous wrappers to inclose its sides, as shown in Figs. 5 and 6. The ends of wrapper *h* overlap, as at *i*, and on a side opposite from the previous overlapped joint *f*. There remain tubular extensions from 120 the ends of the article which are to be folded. The tubular wrapper extension at each end of the article may be conveniently subdivided into folds, as side folds *j*, and upper and lower folds *k* and *l*, respectively. In 125 the illustrated embodiment of the machine, both side folds *j* and lower folds *l* are simultaneously operated upon by a rotary folding

blade by which folds *j* are laid flat against the ends of the articles and fold *l* vertically downward away from the articles, as shown in Fig. 7. A folding blade then lays folds *k* 5 flat against the ends of the articles, as shown in Fig. 8. Folds *l* are carried from the position shown in Fig. 7 flat against the ends of the articles by stationary folders, and, as the folds *l* come into the position shown in Fig. 8, adhesive, as indicated at *m*, is applied thereto, so that the folds *k* and *l* when overlapped will be sealed.

The general frame structure and main driving connections of the machine will first be described with particular reference to Figs. 1^a and 1^b. A represents a suitably supported main table or bed-plate, and supported therefrom and in spaced relation thereabove by a series of columns C is a frame 15 B. Mounted upon the latter in spaced relation are magazines *n*, *o* and *p*, which are adapted to contain the circulars *c*, bands *e*, and wrappers *h*, respectively. The cardboard *b* is supplied in continuous strip form 20 from a roll (not shown). At intervals along bed A and arranged in spaced parallel relation are vertical chutes *r*, *s* and *t* into which the cardboard *b* and circular *c*, the band *e*, and the wrapper *h*, respectively, are fed by 25 suitable means. Intermediate chutes *r* and *s* and rotatably supported from bed A to turn on a horizontal axis is a tumble-box 26. Intermediate chutes *s* and *t* and similarly mounted to turn on a similar and parallel 30 axis is a tumble-box 27, and beyond chute *t* and similarly mounted is another tumble-box 28. Each tumble-box has two diametrically-opposed pairs of jaws 29 between which article *a* may be positioned, and at 35 least one jaw of each pair is yieldable. The tumble-boxes, when at rest, are positioned as illustrated, so that jaws 29 lie horizontal and parallel with bed A. The space between the chutes *r*, *s* and *t* and the adjacent tumble-boxes is filled by bridges 30 to afford a track 40 which is disposed in the same plane as the lower jaws of the turret and upon which the article may ride. Stationary side guides 31 are preferably provided to confine the articles to straight line travel on the bridges and in a line at right angles to the axes of the tumble-boxes. Located in the same plane as the upper jaws 29 of the tumble-boxes are 45 yieldable walls 32 and 32' which engage the tops of the articles and hold them to the bridges 30. The members 30, 31 and 32 thus form chutes through which the articles may be propelled in a manner to be described.

Below bed A and arranged in spaced parallel relation with the axes of the tumble-boxes are cam-shafts 33, 34 and 35, of which the intermediate shaft 34 is adapted to be driven from a suitable source of power. Shafts 33 and 35 are driven from shaft 34 by

chains 36 and 37 and suitable sprockets. Arranged at right angles to shaft 33 and driven therefrom by the bevel gears shown is a horizontal shaft 38 (Fig. 1^a). A Geneva cam 39 is rotatably supported above and with its axis parallel to shaft 38, and this cam is 65 adapted to be turned intermittently by a driving roll 40 which, although shown largely as broken away in Fig. 1^a, is fixed on the left end of shaft 38. Cam 39 drives by a gear train 41 a shaft 42 which is arranged in the same horizontal plane as the axes of the tumble-boxes but at right angles thereto. The shaft of each tumble-box is connected to shaft 42 by bevel gears, as indicated in Fig. 15 in connection with the shaft 80 43 of the tumble-box 27. Shaft 42, in Figs. 1^a and 1^b, has been broken away intermediate its ends to reveal other and more important mechanism, but it will be readily understood that it is so arranged as to simultaneously 85 turn all the tumble boxes, and it is to be understood that the gear train 41 and cam 39 are so designed that each tumble-box is turned intermittently by half a revolution.

The means for feeding the cardboard *b* 90 into chute *r* will next be described with reference to Fig. 1^b. The cardboard in continuous strip form is taken from a suitable supply roll (not shown) and passes between a pair of gear-connected feed rolls 44. The latter are continuously driven by a gear 45 on a shaft 46 which, in turn, is driven from the described shaft 33 by a chain 47 and suitable sprockets. The cardboard strip passes from upper roll 44 to and between a second 100 pair of feed rolls 48, which are intermittently driven at a higher speed than the feed rolls 44. The former act as a "slackener" to loosen a length of the strip from the supply roll, and the rolls 48 operate to feed 105 the loosened length at relatively high speed into the machine. The chute *r*, as shown in Fig. 1^a, has a divided upper end, and the cardboard *b* from rolls 48 passes into the left branch of the chute. One of the feed rolls 48 110 has fixed thereto a pinion 49 which is driven from a gear 50 loosely mounted on a stud 51. Fixed to gear 50 is a ratchet 52, which is adapted to be driven in one direction by a pawl 53. Pawl 53 is carried by a lever 54 115 which is loosely fulcrumed on stud 51 and is connected by a link 55 to the upper end of a lever 56. The latter is pivoted to bed A and intermediate its ends has a roll which rides in a path-cam formed in one face of a disk 57 fixed on the described shaft 46. This cam is constructed to reciprocate lever 56 at properly timed intervals and, due to the pawl and ratchet arrangement, the strip *b* is moved only on the forward stroke of the 120 lever. The cam is also constructed to cause a measured length of the strip *b* to be fed into chute *r*, and this length is such that the bot-

tom edge of the strip rests upon the bottom of the chute. After the strip *b* has been fed into the chute as described, the strip is severed on a line closely adjacent the top of the chute by a pair of shear blades 58. The right-hand blade 58 is stationary and the other movably mounted in a suitable manner. The movable blade 58 is connected by a link 59 to one end of a bent lever 60 which is pivoted at its other end to frame B. Intermediate the ends of lever 60 is a roll which rides in a path-cam formed in the opposite face of disk 57 from the cam heretofore described as operating the lever 56. The operating cam for the shears is constructed to close the blades 58 immediately after the rolls 48 come to rest and to thereafter open the blades to permit another measured length of the strip to be later fed into chute *r*.

The means for feeding the folded circulars *c* into chute *r* will next be described with reference to Figs. 1^a, 9, 10 and 11. Referring first to Fig. 9, the folded circulars in magazine *n* are supported along their front and rear edges by members 61 and 62, respectively. The former member is so constructed as to permit free angular extension of the lower fold *c'* from the upper fold of the circular. The latter may then be engaged between its folds and carried horizontally out of the magazine by an ejector 63 which, as shown in Fig. 11, has a forked forward end to span the central portion of member 61. The side portions of the latter are beveled to permit the passage of the forked portions of the ejector 63. Adjacent the exit of magazine *n* are a pair of pulleys 64 (Figs. 1^a and 11) connected as shown in Fig. 9 by intermeshing gears, and the axes of the pulleys lie in the same vertical plane. Adjacent the entrance end of the described chute *r* are two idler pulleys 65, the axes of which lie in the same horizontal plane. Each pulley 64 is connected to a pulley 65 by a belt 66, and the arrangement is such that adjacent laps of the belt are contiguous and travel in the same direction—namely, downwardly toward chute *r*. The circular removed from magazine *n* by ejector 63 is carried into the bight of pulleys 64 (the forked portion of the ejector being arranged to straddle the pulleys and belt) and between the contiguous laps of belts 66 which thereafter carry the circular into the right-hand branch of the chute *r* and deposit it in parallel and closely-adjacent relation with the cardboard *b*. The pulleys 64 are gear connected as described so that one drives the other and in an opposite direction, and one of the pulleys, as shown in Fig. 1^a, is driven by a chain 67 and suitable sprockets from a shaft 68, which

is the operating shaft for magazine *o*, as will appear. Magazine *p* has a similar operating shaft 69, and the shafts 68, 69 and the main drive shaft 34 are interconnected by a sprocket chain 70 so that each of shafts 68 and 69 and lower roll 64 turn in the same direction. The rolls 64 and belts 66 then travel continuously.

The ejector 63 is operated intermittently by a path-cam 71 which is fixed on the described shaft 46. An arm 72, having a roll 75 to ride in cam 71, is slotted at one end to receive shaft 46, which functions as a guide for one end of the arm. Above cam 71 is a pinion 73, and the upper end of arm 72 constitutes a rack to engage and operate the pinion. A roll 74 holds the rack arm in engagement with the latter. Fixed to pinion 73 is a gear 75, which meshes with a rack 76, fixed to the described ejector 63. Thus, a substantially vertical reciprocation of arm 72 will reciprocate ejector 63 horizontally. Cam 71 is constructed to move arm 72 downwardly and thus move ejector 63 to the right to deliver a circular *c* into the belts 66 in time for the latter to deliver the circular into chute *r* substantially simultaneously with the cardboard *b*.

The means for simultaneously wrapping the cardboard *b* and circular *c* will next be described with reference to Fig. 1^a. The articles *a* are suitably positioned upon the first bridge 30, as by a conveyer 77 the upper lap of which travels horizontally in the plane of the bridge and at right angles to the passageway formed by members 30 and 31. The articles thus positioned are carried along the first bridge 30 and into the tumble-box 26 by a plunger 78 which is mounted to reciprocate on bed A. Plunger 78 is connected by a link 79 to the upper end of a lever 80, and the latter bears a roll which rides in a path-cam 81 fixed on the described shaft 33. The lever 80 is pivoted at a point considerably below the cam-engaging roll thereon, but owing to space limitations, the lower end of the lever has been broken off. It will be readily understood, however, that the arrangement is such that plunger 78 may be moved from the position shown in Fig. 1^a into a position wherein its forward and article-engaging end lies substantially in the plane of the left-hand edges of the jaws 29 of the left-hand pocket of tumble-box 26. Cam 81 is constructed to move the plunger immediately after the cardboard *b* and circular *c* have been fed into chute *r* and before the tumble-box 26 commences its movement, and to then retract the plunger and hold it retracted until another cardboard and circular have been fed into chute *r*.

The tumble-box 26 will next be described with reference to Figs. 1^a, 12 and 13. In each pocket of the tumble-box is a plate 82,

and the two plates are connected together by a pair of rods 83 which are radially slideable in the turret. Thus, a movement of one plate 82 radially inward will move the other plate radially outward, and vice versa. Slidably mounted in each plate 82 is a package-engaging member 84, which is normally held extended from the plate by suitable springs, as indicated. Each member 84 has two spaced wedge-like edges 85 which, when the article and wrappers *b* and *c* are thrust thereagainst by the plunger 78, operate to crease the wrappers, as will later appear.

The plates 82 are, however, movable by means independent of the plunger 78. Referring to Figs. 12 and 13, adjacent each side of the tumble-box and parallel with rods 83, a rod 86 is slidably mounted on bed A and fixed to each rod is an arm 87 which has a part projecting toward the adjacent rod 83 into such position that it may engage and move the right-hand plate 82 radially outward without interfering with the movement of the tumble-box. Each rod 86 is connected by a link 88 to the upper end of a lever 89, which, as indicated in Fig. 1^a, is suitably fulcrumed, as is the lever 80 heretofore described, at the extreme lower part of the machine, which part has been broken away in the drawings on account of space limitations. Each lever 89 has a roll to engage a cam on shaft 83. One of these cams is arranged on each side of the cam 81, so that in Fig. 1^a neither appear, since one is broken away and the other lies behind cam 81. It will readily be understood, however, that the operating means for rods 86 are such that the arms 87 may engage and move the right-hand plate 82 to carry the article *a* from the right-hand pocket of the tumble-box into the position shown on the second bridge 30.

It will be appreciated, however, that to thus move the articles, the right-hand plate 82 and particularly its spring-pressed member 84 must travel beyond the periphery of the tumble-box, and, since the plates 82 are not movable radially inwardly by the described arms 87, means must be provided to move the plates 82 to the left a sufficient distance to prevent the right-hand spring-pressed member 84 from striking on bridge 30 when the turret is turned. This result is accomplished by two diametrically-opposed plungers 90 which, as best shown in Fig. 1^a, are arranged to slide radially in the tumble-box and parallel with and between rods 83. A spring 91 is interposed between the two plungers 90 and acts to force each radially outward to the extent permitted by stop-plates 92. Now, when right-hand plate 82 has been moved as described so that its member 84 just begins to pass beyond the periphery of the tumble-box, the left-hand plate 82

engages the adjacent plunger 90 and moves it, thereby compressing spring 91. As soon as arms 87 move away from right-hand plate 82, the latter is then moved to the left by the expansion of spring 91 until its member 84 has been retracted sufficiently to permit the tumble-box to turn.

It will be recalled that the plunger 78 is operated immediately after the cardboard strip *b* has been severed. The article *a*, engaged by the plunger, is carried against the cardboard *b* and circular *c*. On continued movement of the plunger, the article and its wrappers are carried past a flap-plate 93 pivoted to the forward face of chute *r*. The movement of the article beyond chute *r* will cause the cardboard *b* and circular *c* to be laid about three sides of the article, as shown in Fig. 2, the flap-plate 93 operating to hold the upper horizontal extensions *b* and *c* until the article and its wrappers have been positioned in the tumble-box 26. Continued movement of the plunger will cause the article to engage the spring-pressed plate 84. Before the plates 82 can be moved by plate 84, the springs of the latter will be compressed and, immediately this compression takes place, the arms 87 are arranged to engage and move the right-hand plate 82. Thereafter plunger 78 and arms 87 are moved in unison to insert an article and its wrappers in one and remove another article and its wrappers from the other pocket of the tumble-box. The wedge-like edges 85 are yieldingly forced against the cardboard *b* and circular *c*, to crease them along the lines of fold. The "fold breaking" operation is a particularly desirable feature where, as here, relatively stiff material as cardboard *c* is employed, for otherwise the material will not lie perfectly flat against the article. Immediately after the positioning of the article and its wrappers in the left-hand pocket of the tumble-box 26, plunger 78 is returned into the illustrated position and plate 84 is retracted as described, by spring 91, a sufficient distance to permit the tumble-box to turn. The tumble-box is then turned half a revolution to carry the empty pocket into position to receive another article and to bring the article, just inserted, into the position shown in Fig. 1^a. As the article nears the illustrated position, the one projecting extension from both the cardboard *b* and circular *c* brushes past a pivoted arm 94, which is yieldingly forced toward the tumble-box, and the projecting extensions are caught and yieldingly held between the arm 94 and tumble-box. The article and its wrapper have now been inverted so that on ejection the projecting end of each wrapper is laid in overlapping relation upon the other end, as indicated in Fig. 3, the folding occurring as the article is

thrust between the second bridge 30 and the spring-pressed plate 32 thereabove.

The mechanism associated with the application of the retaining band *e* to the article and the previously applied wrappings *b* and *c* will next be described. As to the feeding of the bands *e*, which are contained in magazine *o*, any suitable means may be employed. For example, means of the type disclosed in the Redington and Milmoe Patent No. 1,117,442, dated Nov. 17, 1914, may be employed. Since such feeding means are well known in the art, detailed description thereof is unnecessary to an understanding of the invention, and accordingly a conventional illustration only has been given in the drawings, it being understood that whatever feeding means is employed may readily be driven from the described shaft 68 (Fig. 1^a) and timed to operate in unison with the ejector 63 heretofore described. The band ejected from magazine *o* is carried to the chute *s* by a pair of belts 95, which are mounted similarly to the described belts 66 and are driven from shaft 68 by a sprocket-chain 96.

The band *e* is wrapped around the article in the same manner as before, but, due to the fact that the article has been inverted by the tumble-box 26, the edges of band *e* overlap, as at *f*, on the side opposite from the joint *d*. A flat-plate 97 and a spring-actuated arm 98 assist in the wrapping of the band in the same way as the previously described parts 93 and 94. The only difference is that two spring-pressed plates 32' are provided to the right of flap-plate 97 to hold the previously applied wrappings *b* and *c* from opening during the passage of the article into tumble-box 27. The plates 32' are arranged one on each side of plate 97 and grip the article near its ends only so as to permit free movement of the plate.

The articles, however, are carried into and out of the tumble-box 27 by different means than those described in connection with tumble-box 26. The particular article-transporting means employed renders unnecessary much of the structure described in connection with tumble-box 26, and tumble-box 27 consists merely of the pairs of opposed jaws 29, one of each pair being yieldable as shown in Fig. 1^a. The rigid jaws, as shown in Fig. 14, are fork-shaped, and the bridges 30 between tumble-boxes 26 and 27 are centrally slotted, as evidenced by the omission of cross-hatching in Fig. 1^a, to permit the movement of the article-feeding mechanism for tumble-box 27, as will appear.

The article feeding and ejecting mechanism will next be described with reference to Figs. 1^a and 1^b. Slidably mounted for vertical reciprocation in suitable guides on brackets *u* which depend from bed A, are

two horizontally-spaced rack-bars 99 which are rigidly connected together by a horizontal frame 100. A segmental gear 101, which is pinned to a stub-shaft 102 rotatably supported in bracket *u*, meshes with each rack-bar 99. Also pinned to each shaft 102 is an arm 103, and the two arms are connected by a link 104 so as to move in unison to raise and lower frame 100 equally at each end. An arm 105 forked at one end to engage the described shaft 34 for guiding purposes, is pivotally connected at its other end to link 104. Arm 105 has a roll, which rides in a path-cam formed in one face of a disk 106 fixed on shaft 34, whereby vertical movements of frame 100 may be obtained. Slidably horizontally on frame 100 is a frame 107 which is connected by a link 108 to the upper end of a lever 109. The latter is loosely fulcrumed at its lower end on a rod 110 which, although broken off in Fig. 1^b, is clearly shown in Fig. 25. An arm 111, forked at one end to ride on shaft 34 for guiding purposes, is pivotally connected at its other end to lever 109 at a point intermediate the ends of the latter and has a roll to ride in a path-cam formed in the opposite face of disk 106 from the cam for arm 105. Thus, frame 107 may be moved horizontally, while frame 100 is moved vertically and the two movements are so co-ordinated that any given point in frame 107 will move in a path which may best be described as a rectangle with slightly rounded corners. Fixed upon frame 107 are four upwardly-extending arms 112 which are movable through suitable openings in the bed A. The first of arms 112 (counting from left to right in Figs. 1^a and 1^b) is likewise movable in the slotted bridges 30 and functions to move the article from the position in which it was left after ejection from the tumble-box 26 into the left-hand pocket of tumble-box 27. The second arm 112 is movable between the forked jaws 29 of tumble-box 27 and functions to eject the article from the tumble-box 27 onto the bridge 30 to the right of the tumble-box. The other two arms are movable in the central slot of the last-named bridge and function to move the articles step by step therealong in a manner later to be described. Obviously, all four arms operate in unison, and the cams in disk 106 are so arranged that these arms move the article simultaneously with the article-feeding means described in connection with tumble-box 26.

The mechanism for feeding and affixing the stamps *g* to join the overlapped ends of the bands *e* will next be described with reference to Figs. 1^a, 1^b, and 16 to 24, inclusive. The articles ejected from tumble-box 27 by the second arm 112 are left in position for the operation of a moistener mechanism and are subsequently carried along bridge 30 by

the third arm 112 into position for the operation of the stamp-affixing mechanism.

The moistener, as best shown in Fig. 19, consists of a container 113, which is adapted to be filled with water and is provided at the bottom with an outlet 114 regulable by a needle-valve 115. Below the outlet 114 and supported from the container is a pad 116, of felt or other suitable absorbent material. The upper portion of the pad receives the regulable discharge from the outlet 114, and the lower portion is arranged to engage and moisten band *e*. Referring now to Fig. 16, an arm 117 is pivoted at 118 to a bracket *v* supported from bed A and is yieldingly held in the illustrated position by a spring 119 attached to a bridge *w* which connects one of the pairs of columns C. Projecting from one side of arm 117 is a lug 120, and spaced from the lug and likewise projecting from the arm is a flat spring 121. The container 113 fits between lug 120 and spring 121, as indicated in Fig. 19, and has a lug 122 which, as indicated in Fig. 1^b, is adapted to engage the top of arm 117. Thus, the container may be removably held by arm 117 and so supported that, when arm 117 is depressed, by means later to be described, the lower face of pad 116 may pass through an opening 123 in the described plate 32 and engage the package to moisten a portion of band *e*.

The stamp-affixing mechanism is operable through an opening 124 in plate 32 (Fig. 1^b) and, in Fig. 16, appears in the rear of the moistening mechanism. A suitable stamp-affixing plunger 125 is slidably mounted in a frame 126 pivoted at 127 to the bridge *w*. A spring 128 operates to normally hold plunger 125 in elevated position as illustrated. Loosely mounted intermediate its ends on a stud 129 fixed in a bracket *x* attached to bed A, is a lever 130, one end of which is forked (see also Fig. 17) to straddle plunger 125 and overlie a collar 131 thereon, whereby when the forked end of the lever is depressed the plunger 125 will be carried through the opening 124 into engagement with the overlapped ends of band *e*. The other end of lever 130 has a roll to ride on a peripheral cam 131. Also loosely mounted on stud 129 and spaced from lever 130 is an arm 132, which as shown in Fig. 17 is rigidly connected by a cross-rod 133 to turn with the lever. Adjacent arm 132 and loosely mounted on stud 129 is an arm 134 which extends to the left of the stud, and the free end of arm 134 is adapted to engage the described moistener supporting arm 117. A pin 135, fixed in arm 134 and projecting laterally therefrom, rests upon a lug 136 on arm 132 to prevent downward movement of arm 133 relatively to lever 130. A spring 137 is arranged between an upwardly-extending lug 138 on arm 134 and a

like lug 139 on arm 132. As the lever 130 is actuated and its forked end moved downwardly, arm 132 through the intermediary of spring 137 moves arm 134 downwardly to engage and move the moistener supporting arm 117. As soon as the moistener pad 116 engages the band *e* with the desired pressure, spring 137 will compress and permit further movement of lever 130, if such is necessary, to cause the stamp-affixing plunger 125 to engage the band *e*. On the return movement of lever 130 arm 134 will be lifted by the upward swinging movement of lug 136. The vertical reciprocatory movement of the moistener and the stamp affixer, operating simultaneously at two spaced points on different packages, is thus obtained from a single cam, and any variation between the stroke of the two members is compensated by the spring 137 or by an adjusting screw 140 which is provided on arm 117 for engagement by arm 134.

The stamp-affixing plunger 125, as described, is slidably supported from a frame 126 which may be swung from the position shown in Fig. 16 to that shown in Fig. 20. An arm 141 fixed to frame 126 is pivotally connected at one end of an arm 142, and the other end of the latter is forked to engage the described tumble-box operating shaft 42. Arm 142 has a roll which rides in a path-cam 143. Referring now to Fig. 15, the described cams 143 and 131 are fixed together and to a bevel gear 144, and these three members are mounted to turn loosely on the tumble-box shaft 42 and are suitably held, as indicated, from axial displacement on the shaft. A bevel gear 145, meshing with gear 144, is rotatably supported on a stud 146 from bed A and is driven by a chain 147 and suitable sprockets from the described shaft 35, as best shown in Fig. 25.

The stamps *g* are connected in continuous strip form as indicated in Fig. 24 and are supplied in a roll which is mounted on an arbor 148 supported from bracket *v*, as shown in Fig. 16. The strip *g* is led from the roll through a suitable slackener device, represented generally by reference numeral 149, to a table 150 (Fig. 20) which is mounted upon the bracket *v*. A plate 151 fixed on a shaft 152 is yieldingly forced against the strip *g* on table 150 by means of a spring 153 (Fig. 16). A substantially U-shaped lever 154 (Fig. 19) is loosely fulcrumed on shaft 152 and is yieldingly forced upwardly, to the extent permitted by the engagement of its cross-bar portion with the under face of table 150, by a spring 155 (Fig. 16). The cross-bar portion of lever 154 bears a blade 156 (Figs. 20 and 22) which functions, as will later appear, to sever strip *g*.

Slidably mounted upon the lower end of frame 126 is a member 157 which is substantially U-shaped in cross-section to engage 130

three sides of the frame and is held to the latter by a plate 158 which engages the fourth side of frame 126. The plate 158 is extended below the member 157 to coöperate 5 as a gripping jaw with a jaw 159 which is secured to the lower end of frame 126. A bow spring 160 is fixed at one end to frame 126 and is engageable at its other end with the slidable member 157 and tends to hold 10 jaws 158 and 159 in closed position. A member 161 is secured to frame 126 near its lower end and has a part passing through a slot in plate 158, as shown in Fig. 21, and the engagement of this part and slot limits the 15 movement of slide 157 in both directions. The member 161 forms a guide for the lower end of the stamp-affixing plunger 125 and is extended to project laterally beyond the frame 126 and downwardly (Fig. 21) to 20 form a cam which is adapted, as shown in Fig. 20, to engage a roll on the U-shaped lever 154 described.

The slide 157 also carries a roll 162 (Figs. 20 and 21) which is adapted to ride upon 25 the upper edge of a strip 163 (Fig. 16) which is fixed at both ends to an arm 164. The latter is pivoted at one end on the described rod 118, and underlying its other end is a lever 165. The latter is pivoted in 30 intermediate its ends to the bracket α and bears a roll which rides in a path-cam formed in one face of the peripheral cam 181, as best indicated in Fig. 15. It will thus be seen that the jaws 158 and 159, which 35 are moved into closed position by spring 160, are capable of being opened by an appropriate movement of lever 165. The strip 163 is curved, and when lever 164 is in raised position, the strip is concentric with 40 the pivot 127 so that the frame 126 may be swung into the position shown in Fig. 20 without causing a radial movement of jaw 158.

During the movement of an article from 45 the opening 123 to opening 124, the lever 165 is so positioned by its cam as to hold lever 164, and thus strip 163, in raised position. The jaws 158 and 159 are therefore opened as shown in Fig. 20. The lever 180 and 50 arm 184 are likewise in elevated position. During the movement of the articles, the frame 126 is swung from the position shown in Fig. 16 to that shown in Fig. 20, and the jaws 158 and 159, being held open during 55 the swinging movement as just described, straddle the end of strip g which projects slightly beyond the end of table 150. As the frame nears the table, member 161 engages the roll on the U-shaped lever 154 and 60 moves the severing blade away from the table into the position shown in Fig. 20. As soon as the frame 126 has been positioned as in Fig. 20, the lever 165 is moved by its cam to allow strip 163 to drop sufficiently so 65 that the jaws 158 and 159 may be snapped

closed by spring 160 to grip the end of strip g . Thereupon, the frame 126 is swung toward the position shown in Fig. 16 and strip g is drawn along plate 150. As soon, however, as strip g has been moved a distance 70 equal to that between the perforations g' (Fig. 24), the member 161 has been moved to release lever 154, which promptly snaps upwardly and severs the strip, leaving a single stamp g held along one edge by the jaws 75 158 and 159. The frame 126 is then moved into the position shown in Fig. 16 substantially at the time when the package comes to rest in under opening 124 and is held in such position until the stamp is af- 80 fixed. With an article at rest in under opening 124 and another article at rest in under opening 123, the cam 181 operates through the connections described to simultaneously depress the moistener pad 116 and the plunger 125 through the openings 123 and 124, respectively, and into engagement with band e . Substantially at the time when the plunger 125 engages the stamp g , the lever 165 is actuated to lift strip 163 and thus open jaws 90 158 and 159, whereby the stamp may be pressed upon the overlapped ends of band e , which ends have previously been moistened to soften the adhesive on the stamp by the pad 116. The overlapped ends of band e 95 having been sealed, the article is now held in a containing sleeve suitable for inclosure by the outer wrapper h .

The mechanism for applying the outer wrappers h to the articles and their previously applied wrappings will next be briefly described. The wrappers h , which are contained in magazine p may be ejected therefrom by any suitable mechanism—for example, that disclosed in the patent above 100 referred to. The ejecting mechanism may be operated from the described shaft 69 to operate simultaneously with the other wrapper-feeding mechanisms. The wrappers ejected from magazine p are carried by 105 belts 166 to chute t in a manner similar to that already described. The articles are removed from the stamp-affixing mechanism by the fourth arm 112 and are carried thereby against the wrapper h , past a flap-plate 115 167 and into the left-hand pocket of tumble-box 28. The latter is identical in construction with the tumble-box 26, except for the omission of the yieldable plates 84. Inasmuch as the tumble-boxes 26 and 28 operate 120 in substantially the same manner, the tumble-box 28 has been shown merely in conventional form, it being understood that parts equivalent to members 82, 83, 86, 87, 88, 90 and 91 are associated with this tumble-box, 125 although not so shown. The movable members of the tumble-box 28 may be operated from levers 168 pivoted on the described shaft 110, which levers may be operated from suitable spaced cams on the described 130

shaft 35. The movable members of tumble-box 28 operate simultaneously with the like members of tumble-box 26 so that it will readily be understood that the wrapper *h* 5 may be completely wrapped around the sides of the article and the articles thrust into a folding box, which is represented generally by reference letter *y*.

The means for folding the end extensions 10 of wrapper *h* will next be described with reference to Figs. 1^b and 25. The folding box *y* is of usual form and comprises a rigid bottom wall 169, two rigid side walls 170 each of which is spaced slightly from the 15 bottom wall, and a yieldable spring-pressed upper wall 172. The left end of each side wall 170 is spaced from the like end of bottom plate 169 a distance substantially equal to the width of the article *a* and has a rearwardly and downwardly inclined projection 173 which extends below the bottom wall 169. The spacing of the ends of the side and bottom walls, as just described, permits the article to be deposited on the bottom wall 169 with the wrapper extensions *j*, 20 *k* and *l* projecting beyond the bottom and top walls to permit end folding operations. The articles ejected from tumble-box 28 come to rest in the folding box *y* in the position indicated by the extreme left of the 25 dotted line representations of the articles *a*, and the articles are propelled intermittently through the folding box by abutment with preceding articles.

30 The wrapper extensions *j* and *l* are folded into the position shown in Fig. 7 by rotary folding blades 174. The latter are fixed in spaced relation on a shaft 175 which is rotatably mounted in bed A and continuously driven from the described shaft 35 by 35 a chain 176 and suitable sprockets. The blades 174 are so driven as to make one complete revolution in the interval required for one cycle of operation by tumble-box 40 28—that is, the interval required for one step of movement of the tumble-box and the ejection of the articles therefrom. The blades 174 swing substantially in the planes of the ends of the articles and act on the 45 wrapper extension after the article has been ejected from the tumble-box 28 and immediately after it comes to rest in the folding box *y*. The rearward of the two extensions *j* is first engaged and laid flat against the 50 ends of the articles and the extension *l* is folded into the plane of said ends but downwardly therefrom. The downward movement of extension *l* causes the foremost extension *j* to be drawn rearwardly and folded 55 flat against the ends of the article, as shown in Fig. 7.

Immediately after the wrapper extensions have been folded as described, and before the blades 174 have moved from engagement 60 with folds *j* and *l*, the extensions *k* are laid

down against the ends of the articles by a pair of vertically-reciprocable folding blades 177. The latter are mounted in suitable axially-spaced relation on a horizontal rod 178, and the ends of the rods are fixed 70 to the upper ends of rods 179 which are mounted in spaced relation to slide vertically in bed A. The lower ends of rods 179 are connected by a cross-bar 180 (Fig. 1^b), and the latter is connected near its central portion to one end of a link 181 which is connected at its other end to a lever 182 (Fig. 25). The latter is pivoted on the described shaft 110 and is adapted to be actuated by a cam 183 fixed on the described 80 shaft 35. Cam 183 is constructed to quickly lower the blades 177 at the proper time and then retract them.

Before either blades 174 or 178 have completely retracted, however, and immediately after the operation of the last-named blades, the article is engaged and moved one step by the ejection of a succeeding article from tumble-box 28. The folded extensions *k* are thus held by blades 177 until they 90 have been transferred to and held by the side walls 170 of the folding box. The extensions *l* are likewise held until they can be transferred to and held by the projections 173, the extensions riding freely in the space 95 between the side walls and bottom wall of the folding box *y*. Upon the ejection of another succeeding article from the tumble-box 28, the article is carried another step and into position for the operation of the 100 adhesive-applying mechanism. As the article moves into such position, folds *l* ride from engagement with projections 173 and, being released, spring upwardly into the position shown in Fig. 8, the top faces of extensions *l* being engaged by the lower edges 105 of the side walls 170.

The adhesive-applying mechanism comprises two glue boxes 184, one on each side of the folding box, and each is suitably fixed 110 to a lever 185 intermediate its ends. The two levers 185 are separately pivoted at one end to upwardly-extending portions of a bracket *z* fixed to bed A. The other ends of levers 185 overlie and rest upon the described horizontal rod 178, so that the glue boxes 184 are raised and lowered simultaneously with the folding blades 177, the lowering being effected by gravity as permitted 115 by rod 178. Each glue box has a roll 186 120 which is turned as its box is raised, but is held stationary as its box is lowered by suitable means, as the ratchet 187 and the serrated bar 188 which is yieldingly held in engagement with the ratchet. Thus, as the 125 glue boxes 184 are lowered, dabs *m* (Fig. 8) of adhesive are applied to folds *l*.

After the application of adhesive to folds *l*, the articles travel step by step through folding box *y* and eventually folds *l* engage 130

an inclined cam 189 on the side walls 170 and are thereby forced upwardly flat against the folds *k* in overlapping relation.

The wrapping of the article having been completed, it remains only to hold the gummed overlapped end folds for a sufficient time to permit the adhesive to set. This is accomplished by a discharge apparatus, which will now be described with reference to Figs. 1^b, 25, 26 and 27. Referring first to Fig. 1^b, a conveyer belt 190 is arranged so that its upper lap travels in the same plane as the bottom wall of folding box *y* and in the direction of travel of the articles through the latter. Belt 190 is driven by a pulley 191 which is fixed to a shaft 192. On the other end of the latter is a sprocket 193 (Fig. 25) which is driven by the sprocket chain 147 already described from cam shaft 35. Two other conveyer belts 194 are arranged so that their adjacent laps travel in the same direction as the upper lap of belt 190 and in spaced vertical planes which substantially form continuations of the side walls 170 of the folding box *y*. Each belt 191 is driven by a pulley 195 fixed on a vertical shaft 196 which is rotatably supported on the bracket *z* already described. The lower end of each shaft 196 is connected by intermeshing spiral gears 197 (Fig. 1^b) to the described shaft 192. The belts 190 and 194 extend to the right from their drive pulleys a sufficient distance and the speed of the belts is such as to permit the articles to be retained in the discharge apparatus until the adhesive has set. The belts return over other and suitably supported idler pulleys (not shown) in the usual manner.

Attached at one end to brackets *z* (Figs. 1^b and 25) and supported at the other end by suitable means (not shown) are a pair of spaced side bars 198 to the upper edges of which is fixed a table 199. The latter underlies the upper lap of belt 190 and holds it from sagging. The side belts 194 are held in the desired plane of travel by other and improved means. Referring to Fig. 26, adjacent each pulley 195 are two rolls 200 which are mounted to slide horizontally and are spring pressed, as illustrated, to force the adjacent laps of belts 194 toward one another to the extent permitted by stop-pins 201. The latter permit the adjacent laps of belts 194 to be moved so that the distance between them is slightly less than the length of the article *a*. The pulleys 195 are so arranged that the adjacent laps of belts 194 near the folding box are spaced a distance greater than the length of the articles. The articles therefore are carried by belt 190 into the converging mouth formed by the two side belts 194 and are gradually engaged thereby. As soon as the articles arrive in

line with rolls 200, the latter are moved outwardly by the article and pressure is applied to the overlapped folds *k* and *l* to force them into intimate relation. Thereafter the folds are held closely pressed together by a plurality of rolls 202 which are made of yieldable material, as rubber or the like. Rolls 202 are arranged in a series, one for each belt 194, and preferably are mounted for adjustment in a line at right angles to their belt, as indicated in Fig. 27.

The operation of the machine will be briefly summarized. The several wrapper-feeding means operate substantially simultaneously to supply the cardboard *b* and circular *c*, band *e* and outer wrapper *h* at spaced points along the straight line path of the articles through the machine. The cardboard, fed in continuous strip form, is severed from the supply strip immediately following the operation of its feeding mechanism. Thereafter the several article-feeding means operate to move the articles. Certain of such feeding means operate to feed articles against their respective wrappers and into one pocket of the adjacent tumble-box, whereby the wrappers are applied in trough-shape to the articles. The other feeding means operate at the same time each to eject an article from the other pocket of a tumble-box. Between the operations of the wrapper and article-feeding means, the tumble-boxes simultaneously turn half a revolution, whereby the articles are inverted so that when ejected from the tumble-boxes their wrappers may be laid in tubular form about the sides of the articles.

Between the last two tumble-boxes and operable while the tumble-boxes are at rest and before the operation of the article-feeding means, the overlapped ends of bands *e* are sealed. While one article is at rest in one position, the overlapped ends of band *e* are moistened, and simultaneously the previously moistened ends of another band *e* on an article at rest in another position are engaged by the plunger 125. The plunger, having been supplied with a stamp *g* by the nipper mechanism, comprising the swinging member 126 and its jaws 158 and 159, forces the stamp against and seals the ends of band *e*.

The outer wrapper only is long enough to extend beyond the ends of the articles, and its tubular end extensions are made while the articles are traveling step by step, still in a straight line but now in abutting relation, through folding box *y*. The adhesive *m* is likewise applied to the end folds of the wrapper as the articles move through the folding box. The wrapped articles pass from the folding box *y* upon the belts 190 and 194 of the discharge apparatus, wherein they are slowly carried to the desired point

of discharge with the gummed seams firmly held into intimate relation until the adhesive has set.

The stamp feeding and applying mechanism are not claimed in this application but are claimed in a separate copending application, Serial No. 235,357, and filed May 18, 1918, as a division of this application.

The invention has been disclosed herein, 10 in an embodiment at present preferred, for the purposes of illustration, but the scope of the invention is defined by the appended claims rather than by the foregoing description.

15 What I claim is:

1. A machine for wrapping articles the ends of which are somewhat rounded, comprising, means to automatically inclose the article except for said ends in a tube of 20 relatively stiff material, means to apply an outer wrapper to said tube leaving extensions from each end of the article, and means to fold said end extensions, all constructed and arranged so that the ends of the article 25 are built out by said tube to form square ends for the end folding operations.

2. A machine for wrapping articles the ends of which are somewhat rounded, comprising, means to wrap strips of relatively 30 stiff material such as cardboard and the like, about the sides of the articles to form inclosing tubes substantially coextensive in length with the articles, means to wrap a retaining band around said tube with its 35 ends overlapped, means to seal the overlapped ends of said band, means to apply an outer wrapper to the articles leaving extensions from each end thereof, and means to fold said end extensions, said inclosing 40 tube arranged to build out the irregular ends of the articles into square form for the end folding operations.

3. A machine for wrapping articles the ends of which are somewhat rounded, comprising, means to automatically inclose the article except for said ends in a tube of 45 relatively stiff material, means to apply a retaining band around said tube, means to apply an outer wrapper to said tube leaving 50 extensions from each end of the articles, and means to fold said end extensions, all constructed and arranged so that the ends of the articles are built out by said tube to form square ends for the end folding operations.

55 4. A machine for wrapping articles the ends of which are somewhat rounded, comprising, means to automatically inclose the article except for said ends in a tube of 60 relatively stiff material, means to wrap a band around said tube, means to seal the adjacent ends of said band to retain the tube in folded position, means to apply an outer wrapper to said tube leaving exten-

sions from each end of the articles, and 65 means to fold said end extensions, all constructed and arranged so that the ends of the articles are built out by said tube to form square ends for the end folding operations.

70 5. A machine for wrapping articles the ends of which are somewhat rounded, comprising, means to wrap a strip of relatively stiff material, such as cardboard and the like, about the sides of the article to form 75 an inclosing tube substantially coextensive in length with the article, means to apply an outer wrapper to the article leaving extensions from each end thereof, and means to fold said end extensions, said inclosing 80 tube arranged to build out the irregular ends of the article into square form for the end folding operations.

6. In a wrapping machine, a tumble-box 85 movable step by step and provided with article-receiving pockets, a movable bottom wall for each pocket, means to feed articles and their wrappers to said pockets, whereby the latter may be wrapped about the article in trough shape, and a yieldable member on 90 said bottom wall engageable with the wrapper to crease the latter along its lines of fold.

7. In a wrapping machine, a tumble-box 95 movable step by step and provided with article-receiving pockets, means to feed articles to said pockets, means to supply wrappers of relatively stiff material into the path of said articles, whereby the wrapper is laid in substantially U-shape about the 100 articles as the latter are carried into the pockets, and means in the tumble-box and coextensive in length with the articles to yieldingly engage the wrapper along its lines of folds to wedge the wrapper tightly about 105 the edges of the article.

8. In a wrapping machine, a tumble-box 110 movable step by step and provided with article-receiving pockets, means to feed articles with their wrappers in substantially U-shape into said pockets, and compressible means in the tumble-box and coextensive in length with the articles to yieldingly engage the wrapper along its lines of fold to press the wrapper into intimate relation with the 115 article and crease the wrapper along its lines of fold.

9. A wrapping machine, including a tumble-box 120 movable step by step and provided with opposed article-receiving pockets, a radially-movable bottom wall for each pocket, means connecting opposite walls so that the insertion of an article in one pocket will eject the article from the opposite pocket, a compressible article-engaging portion on 125 each wall, means to feed articles and their wrappers to the pockets, and means operable after said portion has been compressed by

the fed article to move said connecting means in unison with the article-feeding means.

10. A wrapping machine, including a 5 tumble-box movable step by step and provided with article-receiving pockets, a movable bottom wall for each pocket, means to simultaneously move the walls of two pockets so that an article in one will be ejected 10 as an article is inserted in the other pocket, a compressible article-engaging portion on each of said walls, and means to feed articles and their wrappers to the pockets, the first-named means being operable after said portion 15 has been compressed by the fed article to move said walls in unison with the article-feeding means.

11. In a wrapping machine, a pair of aligned trackways, the delivery end of one 20 being spaced from the receiving end of the other, an intermittently-movable tumble-box having opposed pockets to align with said trackways when the tumble-box is at rest, and means to simultaneously move an article 25 from one trackway into one of said pockets and remove an article from the opposite pocket onto the other trackway, said means comprising two spaced article-engaging members movable simultaneously in a closed 30 loop path which is intercepted by the path of the articles, and timing devices to coordinate the movement of the tumble-box with the movement of said members so that the latter cross into and out of the path of 35 the articles while the tumble-box is at rest and so that the cycle of movement of said members is completed during the movement of the tumble-box.

12. A wrapping machine, comprising, 40 means to wrap articles leaving two wrapper extensions to be subsequently folded in overlapping relation against the article, means to move the articles step by step, a folding device operable as the article comes to rest 45 in one position to lay down one of said extensions, a device operable as the articles come to rest in another position to apply adhesive to the other of said extensions, means to move one of said devices while the 50 articles are at rest, means connecting said devices so that an operation of one effects a simultaneous operation of the other, and means to fold the gummed extension against the folded extension.

13. A wrapping machine, comprising, 55 means to wrap articles leaving two wrapper extensions to be subsequently folded in overlapping relation against the article, means to move such articles step by step, a reciprocable blade operable as the articles come to rest in one position to lay down one of 60 said extensions, an adhesive-applying means operable on the other of said extensions when the articles come to rest in another

position, a lever pivotally supported at one 65 end and supporting intermediate its ends the last-named means, the other end of said lever being engaged with said blade so that a reciprocation of the blade effects a swinging movement of said lever and the adhesive-applying means, and means to fold the last-named against the first-named extension.

14. A wrapping machine, comprising, 70 means to wrap articles leaving two wrapper extensions to be subsequently folded in overlapping relation against the article, means to move such articles step by step, a vertically-reciprocable blade operable as the articles come to rest in one position to lay 75 down one of said extensions, an adhesive-applying means operable on the other of said extensions when the articles come to rest in another position, a lever pivoted at one end to swing in a vertical plane and supporting intermediate its ends the last-named means, the other end of said lever arranged to rest upon and be held by gravity to a part 80 of said blade, whereby a reciprocation of the latter will simultaneously move the adhesive-applying means, and means to fold the last-named against the first-named extension.

15. In a wrapping machine, means to wrap articles including means to form 90 gummed overlapped seams in their wrappers, a conveyer upon which the wrapped articles are deposited, two belts adjacent laps of which are arranged to travel in spaced parallel relation to engage conveyed 95 articles and hold the gummed seams from opening, means to drive said conveyer and belts in the same direction and at equal speed, and rolls having peripheral portions 100 of yieldable material adapted for engagement with one of said laps to yieldingly force the latter against the articles.

16. In a wrapping machine, means to wrap articles including means to form 110 gummed overlapped seams in their wrappers, a conveyer upon which the wrapped articles are deposited, two belts adjacent laps of which are arranged for the major portion of their travel in spaced parallel relation and in their travel adjacent the 115 entrance end of said conveyer in slightly convergent relation, said laps arranged at right angles to the conveyer and adapted to engage the gummed seams of the articles carried thereby, means to drive the conveyer 120 and belts at the same speed and in the same direction, rolls of non-yielding material to engage said laps as they commence their travel in parallel relation, means to yieldingly force said rolls against their laps, and other yieldable rolls to engage said laps 125 after their engagement by the first-named rolls.

17. In a wrapping machine, means to wrap articles including means to form gummed overlapped seams in their wrappers, a conveyer upon which the wrapped articles are deposited, two belts adjacent laps of which are arranged for the major portion of their travel in spaced parallel relation and in their travel adjacent the entrance end of said conveyer in slightly convergent relation, said laps arranged at right angles to the conveyer and adapted to engage the gummed seams of the articles carried thereby, means to drive the conveyer and belts at the same speed and in the same direction, rolls of non-yielding material to engage said laps as they commence their travel in parallel relation, means to yieldingly force said rolls against their laps, and other rolls to yieldably engage said laps after their engagement by the first-named rolls. 15 20
